DESIGN FOR A GARTER

William Govan, Buffalo, N. Y., assignor to Condor Products, Inc., Buffalo, N. Y.

Application May 11, 1937, Serial No. 69,287

Term of patent 14 years

To all whom it may concern:

Be it known that I, William Govan, a citizen of the United States, residing at Buffalo, Erie County, State of New York, have invented a new, original, and ornamental Design for Garters, of which the following is a specification, reference being had to the accompanying drawing, forming a part thereof.

In said drawing:

The figure is a perspective view of a garter showing my new design.

I claim:

The ornamental design for a garter as shown.

WILLIAM GOVAN.
